(57) **CLAIM**

The ornamental design for a brush cover, as shown and described.

DESCRIPTION

FIG. 1 is an isometric view of a brush cover illustrating my new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a back elevation view thereof;

FIG. 7 is a front elevation view thereof;

FIG. 8 is a cross-section view of the brush cover taken in the direction of line A-A shown in FIG. 2; and,

FIG. 9 is an isometric view of the brush cover of FIGS. 1-8 shown on a brush.

The brush illustrated in broken lines in FIG. 9 forms no part of the claimed design.
